Attorney

UNITED STATES PATENT OFFICE

CHARLES LEE WATSON, OF STRAWN, TEXAS

RADIO DIAL AND LOG

Application filed February 21, 1929. Serial No. 341,761.

This invention relates to new and useful improvements in radio devices, and particularly to dials and logs therefor.

One object of the invention is to provide a simple device by means of which the operator may turn the knob of the tuning device of the set, until the call letters of a desired station appear through an opening in the panel of the set.

10 Another object is to provide a device of this character which is simple in construction, easy to operate, and which is accurate and effective in its use.

Other objects and advantages will be apparent from the following description when taken in connection with the accompanying drawing.

In the drawing:

Figure 1 is a front elevation of a portion 20 of the panel of a radio receiving set, showing the dial and log through the opening therein.

Figure 2 is a top plan view of the invention and portions of the receiving set.

25 Figure 3 is a vertical sectional view on the line 3—3 of Figure 2.

Figure 4 is a vertical sectional view on the line 4—4 of Figure 3.

Referring particularly to the accompanying drawing, 10 represents a portion of the front panel of a radio receiving set 11, in which is formed a vertical slot 12, having a hair, or very fine wire 13 extending longitudinally and centrally therein. Mounted 35 on the base 14, of the set 11, immediately in rear of the panel 10, and the said vertical slot 12, is a vertical stub shaft 15. A horizontal disk 16, having a central opening 17, and a tube 18 rising from one face of the 40 disk in surrounding relation to said opening, is disposed on the said shaft 15, as shown in the drawing. Disposed in the upper end of the tube 18 is the depending stub shaft 19, formed on the lower end of the

45 cylinder 20^a, a set screw 20 being engaged through the said tube 18 for engagement with said shaft 19, whereby to hold the cylinder and disk together for simultaneous rotation, and whereby the disk and tube will 50 rotate on the stub shaft 15. Formed on the

lower end of the cylinder is a small circumferential flange 21, which is spaced from the face of the cylinder to form a receptacle in which is received the lower edge of the sheet 22, on the outer face of which are printed the call letters of various broadcasting stations, and a mark which is adapted to be brought into juxtaposition with the hair or wire of the panel slot. The upper end of the sheet 22 is held in place on the cylinder by means of the spring band 23. Disposed through the panel, adjacent the shaft 15, is the horizontal shaft 24 of the control of the set, said shaft having the knob 25 on its outer end, outwardly of the panel, and a disk 26 thereon, inwardly of the panel. A pin 27 projects from the peripheral face of the disk 16, while a similar pin 28 projects from the periphery of the disk 26. Engaged around the said disks 16 and 26, and 70 is the belt 29, said belt having suitable openings for receiving the pins of the disks, whereby to prevent slipping of the belt and to insure the proper driving action between the disks. It will be noted that there is a line drawn around the upper end portion 75 of the sheet 22, and that degrees are marked along said line, with numbers above the line representing wave lengths, in meters, or kilocycles. It will further be noted that the station call letters are at points vertically downward from different degree marks of the line, which correspond to the kilocycles at which the particular stations are operating. Beneath each of the sets of call letters is a horizontal line with a central point directed downwardly, and when the drum or cylinder 20 is rotated, the operator makes 80 sure that this central point is in direct line with the hair or wire of the panel slot. The drum is adapted to be rotated, when the operator turns the knob 25 to tune in the desired station, until the call letters of the station appear in the slot 12.

Attention is directed to the fact that the disks 16 and 26 are of the same diameter so that the cylinder 20, and the shaft 24 rotate at identical speeds, with the result that condensers operated by the shaft, will be operated at the same degree as the cylinder,

with the result that the proper station call letters will appear in the slot 12.

What is claimed is:

In an indicating device for a radio receiving set, the combination with the condenser actuating shaft, of a vertical stub shaft mounted adjacent the actuating shaft, a disk having an integral tubular portion disposed for rotation on said stub shaft, a vertical drum having a depending stub shaft removably secured within said tubular portion for rotation with said disk, the lower end of the drum having a peripheral upstanding flange spaced from the face of the drum, a sheet of flexible material engaged around the drum with its lower edge retained between the drum and flange, a resilient band retaining the upper end portion of the sheet, and operative driving connections between the said actuating shaft and the drum shaft.

In testimony whereof I affix my signature.

CHAS. LEE WATSON.
